UNITED STATES PATENT OFFICE.

EUGENE S. SANDBERG AND LELAND E. NEWELL, OF SPRINGFIELD, ILLINOIS.

DUPLEX METHOD OF AND APPARATUS FOR SENDING TELEGRAPHIC MESSAGES.

1,338,452.

Specification of Letters Patent.

Patented Mar. 9, 1920.

Application filed July 21, 1917. Serial No. 181,973.

To all whom it may concern:

Be it known that we, EUGENE SIXTEN SANDBERG and LELAND BEEMAN NEWELL, citizens of the United States, residing at the 5 city of Springfield, in the county of Sangamon and State of Illinois, have invented certain new and useful Improvements in Duplex Methods of and Apparatus for Sending Telegraphic Messages, of which the following 10 ing is a specification.

This invention doubles the capacity of an ordinary single-wire line for Morse telegraphy even over its capacity when operated by a duplex machine such as is now in ordinary use, and reduces the cost of installations at stations by doing away with the relays and local batteries at stations, the Morse sounders operating with the main-line current. With one single-wire Morse circuit 15 such as is now in common use and the addition of this invention the effect is obtained of two single-line Morse circuits consisting of two separate complete and independent circuits. As wire is the greatest expense of a 20 telegraph system, this invention is of vital importance, because it enables one wire to do the work of two. Other economies will hereinafter appear.

Primarily these results are due to the substitution of alternating current electricity 25 for the direct current now customary in Morse telegraphy, and the sending of a message in one direction on the pulsations in one direction on a wire of that current and simultaneously another message on the same 30 wire on the pulsations of that current traveling in the opposite direction. This mode of using the alternating current for the purpose stated is made possible by the dividers which 35 constitute part of this invention and which 40 are hereinafter described.

It is to be understood that the words positive and negative used herein are relative terms arbitrarily applied like algebraic symbols, and that the current or pulsations, 45 traveling in one direction and herein termed positive would as well have been denominated negative and vice versa. Merely for the purposes of description the current flowing in 50 one direction is called positive and the opposite negative.

In the accompanying drawings forming part of this specification and in which like

numbers of reference denote like parts wherever they occur,

55

Figure 1 is a diagrammatic view;

Fig. 2 is a top plan view of a divider cell;

Fig. 3 is a side elevation of such cell;

Fig. 4 is a diagrammatic view of the wiring at a station where an incandescent lamp 60 is provided to be cut in when the sounder is cut out; and

Fig. 5 is a diagrammatic view showing separately the wiring at the said station of the switch, the sounder, and the incandescent 65 lamp.

A pair of dividers, 1 and 2 respectively, is located at each station, and each divider is composed of a cell or jar 3 containing a liquid 4 having certain chemical properties 70 or characteristics, each of the said cells having, also, a pair of terminals, the metallic plates 5 and 6 of which are at least partially submerged in the said liquid 4, acting as an electrical conductor therebetween, and 75 which are supported preferably by means of a hook or hooks 7 engaging the edge 8 of the jar 3.

One of the said metal plates is composed 80 of one metal or other suitable material, and the other of another. Each is provided with a binding-post 9, to which a wire 10 or 11 is connected, which wires 10 and 11 are branch wires from the main or line wire 12. The main line wire 12 branches into two wires at 85 each station, which combine in or lead back to wire 12 in leaving the station, which wire 10 may be termed the positive wire and 11 the negative wire, divider 1 being designated as positive and divider 2 negative, and plate 90 5 denominated positive and plate 6 negative.

Thus the plates 5 and 6, with their respective binding-posts 9, constitute terminals, which by the chemical action thereon of the liquid 4 act as selective terminals to divide 95 the alternating current into positive and negative halves or phases, the positive part consisting of those pulsations of the current that travel in one direction, while those that travel in the opposite direction are herein 100 termed negative.

One of said plates, as 5, may be of aluminum and the other, as 6, of lead. It will be understood, however, that these metals or materials are mentioned only by way of 105 illustration and not in a restrictive sense, as

any other metals or materials may serve instead of the aforementioned substances adapted to perform the selective function stated and fall within the scope of the appended claims.

It is also observed that the liquid 4 may be produced and constituted as herein stated and be attended with the desired chemical action (or reaction) in conjunction with 10 aluminum and lead plates 5 and 6.

The liquid bath or solution 4 may consist of about one-half pound sodium phosphate dissolved in about one pint of distilled water and to this solution may be added a saturated 15 solution of ammonium phosphate in distilled water, the same being mixed by pouring both into the jar.

It is a matter of experimental knowledge that certain metals and materials possess a 20 natural attraction or affinity for the pulsations of an alternating electric current traveling in one direction, while other metals and materials possess a like attraction or affinity for the current traveling in the opposite 25 direction. Thus, if an alternating current be passed from the generator in Fig. 1 through the wire 12 that branches into wires 10 and 11, and the positive plate 5 is at the side of divider 1 that is nearer to the generator than the negative plate 6 in divider 1, while in divider 2 the negative plate 6 is closer to the generator than the positive plate 5 in divider 2, the pulsations of the alternating current that travel 30 in one direction and which we call the positive current select for themselves the positive plate 5 terminal as their line of affinity or of least resistance; and as all other dividers to the end of the line, *e. g.*, the right-hand side of Fig. 1, are similarly set or arranged, so that in one jar or cell 3 out of each pair at a station or the like the positive plate will be nearer than the negative plate to the generator and in the other jar 3 the 35 negative plate will be nearer than the positive plate to the generator, the positive current will be in effect a direct current in one direction on the single wire, while the negative current (consisting of the pulsations 40 in the opposite direction and which select for themselves the negative plate 6 terminals as their line of affinity or of least resistance) will be in effect a direct current in the direction opposite to the positive current.

50 In this explanation or view, it will be understood that the pulsations in either direction have greater affinity for the material of which positive plate 5 is composed than for that of plate 6, and find same first presented to them coming toward the generator along the lefthand side of Fig. 1, just as the other pulsations found them first presented going away from the generator along the righthand side of Fig. 1.

65 In the present Morse telegraphy and in

our system, the stations are connected in series, but our system differs in that each station is provided with a pair of dividers 1 and 2 and a key and sounder wired in conjunction with divider 1 and a separate key 70 and sounder wired in conjunction with divider 2 (see the diagram in Fig. 1). One set of these instruments operates, and can operate, only by means of the positive current for the time being and the other by 75 the negative current for the time being, as hereinbefore described. This enables two operators to use the same wire at the same time, while in ordinary Morse telegraphy only one operator can transmit a message on 80 one wire at one time. The reason for our result is that, by dividing the alternating current as aforesaid, the one wire is in effect split into two wires where the current enters 85 the station.

Having passed through the dividers and the respective instruments, the two direct currents (or the two halves or phases of the alternating current) pass into the wire 12 again as alternating current.

When the Morse key on one of the parts of the split wire is open, only a current traveling in one direction can pass over the line at any point. When the key on the other part of the split wire is open, only 90 a current in the other direction can pass. When both keys are open, no currents are passing over the line. When both keys are closed, an alternating current is passing over the line, but is split into two direct currents at 95 the stations, traveling in opposite directions. It will be seen that two telegraph operators can transmit a message at the same time, one of them using the positive current side, and the other operator using the negative current side. By this arrangement, we have 100 exactly the effect of two wires under the system of wiring now in vogue. One side of the wire line may be operated as an ordinary line connected to all stations, while simultaneously the other side is used as a through 105 trunk line.

When all the keys on the line are closed, and an alternating current is put into the wire from one terminal station (*e. g.*, the generator in Fig. 1), the Morse sounders will vibrate so as to give forth a sharp, metallic humming note, the variations in length of which when broken by a key determine 115 whether the signals are dots or dashes. It 120 is quite important that the armature bar of the sounders be raised considerably above the heads of the magnet cores—approximately one-eighth inch—to avoid sticking of the sounding bar. To obtain the best results, the bar should be so adjusted as to leave only the slightest margin of play between the sounding contacts. This will give 125 a sharp singing tone that is easily read by a telegraph operator.

This system presents the advantage of allowing at will either two sendings or two receivings without changing the apparatus at any terminal or intermediate station, 5 whereas the present duplex system allows only a sending and a receiving from each of two terminal stations.

By "sending" and "receiving" is meant the mechanical means for sending messages and 10 the mechanical means for receiving messages. In the present duplex machine, these means differ, in that one can not send a message by using a receiving means. The insertion of a key in the receiving means 15 would not enable one to send a message from the home to a distant station. In the duplex the receiving means is tuned to catch an electric vibration sent from a distant station. The insertion of a key in the receiving 20 means would not enable one to send a signal through these delicately arranged instruments in such manner as to reproduce the signal at the other end.

The advantage of having two sendings or 25 two receivings lies in the fact that all of one relay point's messages may have been transmitted, while the other relay point still has several hundred on hand. With our outfit two men can be placed at the work of sending, while with the present duplex, only 30 one sending is available.

It should be borne in mind that with this system, one man at any station can send to a man at any other station and simultaneously 35 another operator at still another station can send to still another station; that two men can send from any one station to two men at any other station, or separately to two stations, or can receive from two operators at 40 the same time; or one station can simultaneously send and receive.

Another advantage of this system over the present duplex is the fact that the installation will remain permanent without constant balancing, etc., as is necessary now 45 with the weather changes. This system provides for two circuits, which are entirely independent of each other. This saves about one hour of time in twenty-four.

50 Another advantage lies in the fact that when it is necessary for the receiving operator at one terminal to "break" (that is, to notify the distant operator to repeat a part of a message not understood), he can do so 55 without delaying the sending operator at the home terminal. Under the system now generally in use, it becomes necessary for the receiver to require the sender to notify the distant receiver in turn to notify the 60 distant sender of the text of a message that is not clear. These "breaks" occur frequently, and are more or less numerous according to the ability of the operators, necessitating the delay of the entire wire traffic, in order to straighten out one receiving 65

operator on the clarity of a message. With our system, the receiver can notify the distant sender without delaying the progress of the other two men. This saves ten minutes per hour. 70

When the use of a repeater is necessary it is provided in duplicate and with a pair of dividers, like a station.

Our apparatus is a doubly-efficient field-set for the United States Army Signal-Corps, and is simple and practical. 75

If for any reason the constant humming of the sounder be objectionable, the sounder when not in use can be cut out by a single-lever double-throw knife switch 13 (or any 80 other suitable switch), which simultaneously "cuts in" an incandescent lamp 14, the sounder 15 being shown in Fig. 4 as within a resonator 16. When the operator desires to take messages, he throws the switch, cutting 85 out the lamp and cutting in the sounder. When the lamp has been cut in, it will give a steady light except when some operator on the line is calling or otherwise using the wire, when it will flare when the key is 90 opened and closed. Such lamps at stations can be used for calling, by making the signals so slowly that the lamp-flashes can be read as dots and dashes. After the call has been read by the lamp, the operator can 95 cut out the lamp and receive the message from the sounder by ear.

Having thus described this invention, we hereby reserve the benefit of all changes in form, arrangement, order, or use of parts, as 100 it is evident that many minor changes may be made therein without departing from the spirit of this invention.

We claim:

1. An apparatus for utilizing alternating current electricity in both its phases in telegraphy consisting of an alternating-current generator, a main wire extending from the said generator to a ground terminal, branch conductors from the said main line, a pair 105 of dividers to which said branches lead, means in the said dividers for splitting the said alternating current into its two phases consisting of pulsations in opposite directions, a double set of Morse instruments in 110 the station, means in each divider adapted to conduct the particular phase of the said alternating current received by it through its said branch conductor to its respective Morse instruments, branch conductors leading from the said double set of Morse instruments back to the main line, an incandescent lamp, and a switch so located as to be adapted to cut out a sounder when not in use and to cut in the lamp at such time and 115 vice versa.

2. An apparatus for utilizing alternating current electricity in both its phases in telegraphy consisting of an alternating-current generator, a main wire extending from 130

the said generator to a ground terminal, branch conductors from the said main line at each station, a pair of dividers at each station to which said branches lead, means 5 in the said dividers for splitting the said alternating current into its two phases consisting of pulsations in opposite directions, a double set of Morse instruments in each station, means in each divider adapted to 10 conduct the particular phase of the said alternating current received by it through its said branch conductor to its respective

Morse instruments, branch conductors at each station leading from the said double set of Morse instruments back to the main 15 line, an incandescent lamp for each sounder, and a switch so located as to be adapted to cut out a sounder when not in use and to cut in the lamp for each sounder at such time and vice versa. 20

In testimony whereof we hereunto affix our signatures.

EUGENE S. SANDBERG.
LELAND E. NEWELL.
